UNITED STATES PATENT OFFICE.

CYNTHIA EDITH VARNEY, OF HEMLOCK, WISCONSIN.

DEVICE FOR HANDLING GENERAL-DELIVERY LETTERS.

SPECIFICATION forming part of Letters Patent No. 613,538, dated November 1, 1898.

Application filed February 25, 1897. Serial No. 624,914. (No model.)

To all whom it may concern:

Be it known that I, CYNTHIA EDITH VARNEY, a citizen of the United States, residing at Hemlock, in the county of Clark and State 5 of Wisconsin, have invented certain new and useful Improvements in Devices to Provide for the Handling of General-Delivery Letters; and I do hereby declare the following to be a full, clear, and exact description of the invention, such as will enable others skilled in the art to which it appertains to make and use the same.

This invention relates to letter-boxes; and the object of the same is to provide a rotatable box for exhibiting letters for the purpose 15 of enabling a person to ascertain whether there is any mail for him without asking the postmaster, the box being so arranged that when the same is revolved the letters may be brought into view, so that it may be ascertained whether there is any mail for a given name without troubling the postmaster.

The invention also consists of certain other 25 novel constructions, combinations, and arrangements of parts, all of which will be hereinafter particularly set forth and claimed.

In the accompanying drawings, forming 30 a part of this specification, Figure 1 is an elevation of my improved letter-box. Fig. 2 is a sectional view of the same, showing the device positioned behind a partition. Fig. 3 is a transverse section on the line 3 3 of Fig. 2, and Fig. 4 is a detail view of one of the spring-clasps for holding the letters.

35 Referring to said drawings, 1 indicates an octagon-shaped box, which is adapted to revolve upon a supporting-post 2, extending therethrough. Upon the bottom of the cylinder is the circular rack 3, which is engaged 40 by the cog-wheel 4, journaled upon the shaft 5, which is supported by the post. Upon the shaft is a crank 6, by means of which it is operated and the box rotated.

Upon the sides of the box, at the upper end 45 thereof, are the letters of the alphabet, "A," "B," and "C" being on one side, and so on through the entire alphabet, each side containing three letters, with the exception of letters "S," "T," "U," "V," "W," "X," 50 "Y," and "Z," which are placed four upon a side. The letters are positioned beneath the

designated letter of the alphabet to which they belong and are secured in position by the spring-clasps 7. These clasps 7 are formed of a single piece of wire doubled and secured at 55 its extremities to the side of the box. The letter is inserted between the surface of the box and the looped portion of the clasp.

In use the box is positioned behind the partition 8 within the postmaster's office, the partition being provided with a glass window 9 just in front of the box. The operating-crank extends through the partition within convenient reach of the public. The letters of persons not owning boxes in which to put their 60 mail are distributed upon the sides of the box according to the letter of the alphabet to which they belong. When any one desires to ascertain whether there is any mail for him, he revolves the box by means of the 65 crank until the side of the same containing the designating-letter of the alphabet to which his name belongs is brought before the glass window. In this position he can glance along 70 down the row of letters under the indicating- 75 letter to which his name belongs, and if there is a letter all that is necessary is to call the attention of the postmaster to the same and receive it. Thus the postmaster is not troubled by persons wishing to ascertain whether 80 there is any mail bearing their name.

This invention is designed more especially for small post-offices, although it could of course be used in the larger offices.

From the above description it will be seen 85 that I have produced a box upon which letters may be secured to be brought into view by persons desiring to ascertain if there is any mail in the office in their name, thus rendering the duties of the postmaster less irk- 90 some by the repeated answering of inquiries regarding the mail of individuals not renting boxes.

Having thus described my invention, what I claim as new, and desire to secure by Letters 95 Patent, is—

The combination with a partition having a transparent plate therein, of a support positioned on one side of said partition, a drum rotatable upon said support, a rack carried 100 by said drum, a shaft journaled at one end in the support and projecting at its opposite

end through the partition, a pinion upon said shaft and adapted to engage the rack, a crank upon the projected end of the shaft for rotating the same, the sides of said drum being lettered to correspond to the letters of the alphabet, and spring-clasps secured on the surface of the drum.

In testimony whereof I have signed this specification in the presence of two subscribing witnesses.

CYNTHIA EDITH VARNEY.
